UNITED STATES PATENT OFFICE

ALBERT WILLIAM KOCH, OF ODELL, NEBRASKA

CIGAR DISPLAY RACK

Application filed December 14, 1929. Serial No. 414,132.

My invention relates to cigar display racks and more particularly to display racks which are designed for use on counters and show cases.

5 The primary object of the invention is the provision of a compact rack which may be placed on the show case to occupy very little space and to display a large number of cigars in the cigar box containers, the purpose 10 being also to leave the show case in such condition that the view of the contents of the show case will not be materially obstructed.

Another of my objects is the provision of a rack which is simple in construction and 15 which may be easily made so that it may be sold at a relatively low price.

Another of my objects is the provision of a rack which will display a large number of cigars in the most attractive form and which 20 will leave the cigars readily accessible and within reach of the purchaser.

Another of my objects is the provision of a foldable rack which is in compact form when not in use, thus making it possible to pack a 25 large number of the racks into small volume for convenience in shipping the racks without danger of injury to them during transportation.

Having in view these objects and others 30 which will be pointed out in the following description, I will now refer to the drawings, in which

Figure 1 is a view in perspective of the entire rack and showing the way in which the 35 cigar boxes may be placed on the rack for display.

Figure 2 is a perspective view of an end portion of the rack showing the method of construction.

40 The frame of the rack includes two side rails 10 and a bottom rail 11 in rectangular relationship. The legs 12 are secured to the side rails 10 by means of the hinges 13 so that the legs 12 are foldable inwardly about 45 the pivots of the hinges 13. The rack is thus supported on the bottom rail 11 and on the legs 12. The length of the racks 12 is such as to give the most desirable inclination to the side rails 10 and to the display rack as a 50 whole.

Connecting the side rails 10 and secured to the bottom rail 11 is a bar 14 the rear surface of which is flush with the rear surfaces of the side rails 10. The front surface of the bar 14 is inset as shown in Figure 2 so as 55 to leave the forward portion of the bottom rail 11 as a ledge for supporting one or more cigar boxes. Since the front surfaces of the side rails 10 and the bottom rail 11 lie in the same plane, the bar 14 would also be inset with reference to the side rails 10 so that the front portions of the side rails 10 would serve as abutments to prevent the cigar boxes from sliding off the edges of the display rack. Other supports 15, 16 and 17 are also provided, 60 all of which are connected at their ends to the side rails 10. The front surfaces of the bars 14, 15, 16 and 17 all lie in the same plane and they serve as supports against which the bottoms of the cigar boxes rest. All of these 65 bars serve also as braces for the display rack as a whole. The bar 17 is also the top rail of the rack.

In use the rack is placed in the position 70 shown in Figure 1 with the legs 12 in their operative position. The lid of the cigar box 18 is then folded back as shown in Figure 1 and the box is placed on the rack with an edge resting on the ledge of the bottom rail 11 and with the bottom of the box resting 75 against the bars 14 and 15. The lid is forced back between the bars 15 and 16 and it serves as a ledge for the box 19.

The rack may be made in any desirable 80 length to accommodate any desired number of cigar boxes. The width also may be increased as desired but it is found that the width which accommodates two cigar boxes one above the other is the most desirable in 85 the average cigar store. A rack of this width may be placed on top the show case without materially obstructing the view of the contents of the show case. The length of the rack is governed largely by the amount of 90 display surface desired. In the usual cases the most desirable capacity of the rack is six or twelve cigar boxes. It is to be understood, however, that the rack may be increased or decreased either in length or width to meet 95 any special requirements. The display rack 100

is so designed that its use complies with the revenue laws which require that the stamp be not completely destroyed until the box has been emptied. If it were necessary to entirely remove the lid from the boxes, the stamp would be practically destroyed but the arrangement permits the folding back of the lid so that the entire stamp remains except at the one place where it is broken in opening the lid.

Having thus described my invention in such full, clear and exact terms that its construction and operation will be readily understood by others skilled in the art to which it pertains, what I claim as new and desire to secure by Letters Patent of the United States is:

A one-piece foldable display rack for open cigar boxes, said rack including a bottom rail and a pair of side rails, a top rail and a plurality of transverse bars connecting said side rails and spaced from each other to provide open spaces therebetween for the open lids of cigar boxes, the forward edges of said transverse bars and said top rail being in the rear of the forward edges of said bottom rail and said side rails whereby the forward portion of said bottom rail will serve as a ledge for supporting the lower tier of cigar boxes, the arrangement being such that a plurality of cigar boxes may rest on the ledge of said bottom rail with their open lids projecting rearwardly into and through the open spaces between said transverse bars to function as ledges for supporting an upper tier of cigar boxes, each of said side rails having a supporting leg hingedly secured thereto whereby the legs are foldable against the rear edges of said transverse bars to thus provide a flat package for storing and shipping.

In testimony whereof I affix my signature.
ALBERT WILLIAM KOCH.
